Lyndon A. Durant, 328 N. California Ave., Chicago, Ill.

Filed Mar. 3, 1965, Ser. No. 84,370

Term of patent 14 years

(Cl. D34—5)

FIG. 1

FIG. 2

FIG. 1 is a perspective view of the simulated pool game table showing my new design.

FIG. 2 is a front elevation thereof.

The side opposite that shown in FIG. 1 is the same as the side shown.

The bottom and rear sides thereof are plain.

The dominant features of the design are shown in full lines.

This is a continuation-in-part of design application Serial No. D. 78,472, filed February 3, 1964, now abandoned.

I claim:

The ornamental design for a simulated pool game table, as shown and described.
